UNITED STATES PATENT OFFICE

2,571,482

CONTAINER

William T. Pettit, Youngstown, Ohio

Application September 26, 1945, Serial No. 618,666

1 Claim. (Cl. 220—31)

1

This invention relates to a container and particularly to a combination container and closure therefor.

The principal object of the invention is the provision of a container and closure therefor.

A further object of the invention is the provision of a container having a closure therefor and incorporating means for locking the closure thereto.

A still further object of the invention is the provision of a container and a closure therefor and incorporating a closure supporting hinge construction.

A still further object of the invention is the provision of a container including a closure and having a secondary closure formed therein.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a top plan view of the container.

Figure 2 is a side elevation of the container with parts broken away and parts in cross section.

Figure 3 is a side elevation of a portion of the container illustrated in Figure 2 and illustrating the locking mechanism in detail.

Figure 4 is a side elevation with parts broken away and parts in cross section illustrating a modified form of the container incorporating a secondary closure in the main closure thereof.

By referring to the drawings and Figures 1, 2 and 3 in particular, it will be seen that a container has been disclosed which consists of a main body section 10 including a bottom 11 and having an outwardly flanged top 12 adapted to receive a closure 13 which is provided with a sealing gasket 14 so located as to engage the uppermost portion of the out-turned flange 12 of the container 10. The container 10 is preferably formed, as best illustrated in Figure 2 of the drawings, from a relatively heavy metal stamping as, for example, 16 gauge steel, in the form of a flanged head which comprises the bottom 11 of the container in assembled form and a cylindrical body section of the body 10 is preferably formed of relatively heavy sheet metal

2

such as, for example, 25 gauge steel. The cylindrical body section and the bottom section are assembled as by welding to form a durable container, it being observed that the bottom section 11 is provided with an upstanding flange 15 which overlies the bottom end of the cylindrical body section of the container 10. This overlying flange which provides for a welding seam between the cylindrical body section 10 of the container and the bottom 11 thereof also provides a reinforcing collar band thereabout which enables the container to resist rough handling. A pair of handles 16 disposed on a vertical axis are located on the container one on the cylindrical body section 10 and one on the side of the bottom section 11, one being immediately above the other, and which location of the handles 16 provides for the convenient handling of the container as in emptying the contents therefrom.

20 The closure 13, which is in the form of a flanged dished-out head of an over-all diameter larger than the largest diameter of the out-turned flange 12 at the top of the container 10, is adapted to be positioned thereover and to

25 register therewith in connection with the rubber sealing gasket 14 which can be formed of any desired type of rubber such as, for example, sponge rubber. In order that the closure 13 may be locked on the container 10, an inturned hook 17 is formed at one side thereof so as to overlie a section of the flange 12 at the top of the container and a slideably mounted cam 18 and operating lever 19 are positioned at the opposite side of the closure preferably in a boss 20 formed thereon.

30 The operating lever 19 of the cam 18 is rotatably positioned in an opening in the boss 20 and thereby enables the cam 18 to be revolved so as to bring it into engagement with the out-turned flange 12 of the container 10 when the cam 18 and operating lever 19 are moved inwardly toward the container 10.

35 It will thus be seen that a simple and durable container and closure has been disclosed, the closure portion of which may be conveniently and simply locked to the container portion through the simple manual actuation of the cam and lever 18 and 19, respectively. In order that the closure 13 may be supported in open relation to the top of the container 10, a supporting 40 hinge-like structure 21 is provided on the section of the container normally lying adjacent the hook 17 formed on the closure. This construction in which the hook 17 is provided with a downwardly inturned end and the supporting structure 21 is formed with an upwardly turned

end, as illustrated in Figure 2, supports the closure 13 on the container 10 when it is in opened position and standing vertically or approximately so with respect to the container 10, and the hook 17 and supporting structure 21 are in engagement.

By referring now to Figure 4 of the drawings a modified form of closure for use with the container will be seen. In Figure 4 a container body 22 is provided with a closure 23, the structure of which is similar in all respects with that of the closure illustrated in Figures 1, 2 and 3 and heretofore described, with the exception that it is provided with a secondary closure 24 which is hinged as at 25 to the closure 23 and is provided with an upstanding, outwardly turned handle 26 to enable it to be conveniently moved into the interior of the container to permit objects to be placed in the container through the opening thus provided. The secondary closure 24 is preferably sprung with relation to the closure 23 as by provision of a flat spring 27 incorporated in the hinge structure 25 and adapted to normally maintain the secondary closure 24 in closed, horizontal relation with the closure 23.

It will thus be seen that a container particularly suited for the reception of rubbish, ashes, garbage, etc. has been disclosed which is provided with a closure which may be locked in position thereon by means of the cam 18 and cam operating lever 19, and which may be supported in open position on the closure by means of the combination hook 17 and supporting hinge 21.

Having thus described my invention, what I claim is:

In a container having a cylindrical body in-

cluding a bottom section affixed thereto, means for supporting a closure with respect thereto, said means including an upturned projecting member formed on the outside of the said cylindrical body and near the upper edge thereof, a closure for the said container comprising a flanged circular disc of a diameter greater than the outer diameter of the upper edge of the said cylindrical body and having an inturned and downturned hook formed on the inside of the flange of the said disc and adapted to engage the said upturned projecting member on the outside of the said container at all times so as to hold the closure in open and closed position on the container.

WILLIAM T. PETTITT.
